CLAIM

The ornamental design for a display rack of helical configuration, as shown and described.

DESCRIPTION

FIG. 1 is a perspective view of a display rack of helical configuration according to my novel design;

FIG. 2 is an enlarged side elevational view of FIG. 1;

FIG. 3 is a greatly enlarged side view of one of the display modules of FIG. 1, shown separately for clarity of illustration;

FIG. 4 is a rear view of the display module of FIG. 3; FIG. 5 is an enlarged fragmentary perspective view of the top of the display rack of FIG. 1, shown without the circular top member for clarity of illustration;

FIG. 6 is a greatly enlarged top plan view of FIG. 1, shown without the circular top member for clarity of illustration; FIG. 7 is a bottom plan view of FIG. 6, shown without the triangular base member for clarity of illustration; and, FIG. 8 is a bottom view of the display rack of FIG. 1 shown on an enlarged scale.

The elements disclosed in broken lines in FIGS. 1, 2, 3, 6, 7, and 8 are for illustrative purposes only and form no part of the claimed design.
